HORIZONTAL AND VERTICAL RIFFLE

Filed Aug. 27, 1928

INVENTOR
RICHARD REA
by *K. A. Dreckman*
ATTORNEY.

UNITED STATES PATENT OFFICE.

RICHARD REA, OF LONG BEACH, CALIFORNIA.

HORIZONTAL AND VERTICAL RIFFLE.

Application filed August 27, 1928. Serial No. 302,255.

This invention relates to a riffle for the separation of metals from the pulp or sand.

An object of my invention is to provide a riffle, the baffles of which extend both vertically and horizontally and which is effective in recovering a maximum amount of the metals from the pulp, sand, or the like.

Another object is to provide a riffle which also acts as a classifier to prevent the large and heavy particles from mingling with the pulp containing the metal.

A further object is to so break up the flow of pulp by means of eddies therein so that the metals are prevented from flowing over the top of the pulp in a scum but are thrown downwardly and deposited on the floor of the riffle.

Other objects, advantages, and features of invention may appear from the accompanying drawing, the subjoined detailed description, and the appended claims.

In the drawing:

Fig. 1 is a fragmentary side elevation of my riffle with parts broken away to show the interior.

Fig. 2 is a fragmentary plan view of the same with the upper perforated plate broken away.

Fig. 3 is a sectional view taken on line 30 3-3 of Fig. 2.

Fig. 4 is a fragmentary perspective view of the upper perforated plate.

Fig. 5 is a fragmentary enlarged plan view of the perforated plate.

Fig. 6 is a fragmentary transverse sectional view of the same.

Fig. 7 is a view similar to Fig. 6 showing the depending lip at an angle.

Fig. 8 is a view similar to Fig. 6 showing the depending figure in another angle.

Referring more particularly to the drawing:

The numeral 1 indicates a sluice box of any desired size and of usual construction.

45 This sluice box is set at an angle so that the pulp travels therethrough by gravity, all of which is usual and well-known in the art. On the floor 2 of the sluice box I provide horizontal riffles 3, the riffles extending trans-

50 versely of the box. The riffle 3 may be constructed in a number of different ways, namely, they may be formed integral with the floor of the box by forming transverse grooves thereon, a separate metal plate may be provided having grooves thereon, or a coarse corduroy may be utilized. The cor-

droy may be either cloth, rubber, or some suitable composition material.

The riffle 3 extends the full width of the box and extends substantially the entire 60 length thereof. A riffle tray 4 is provided in the box 1 over the riffle 3, said tray extending substantially the full width of the box and over the length thereof. The tray 4 is provided with a series of rows of holes 65 5 so that the pulp is permitted to pass downwardly through the tray. In cutting the holes 5 the lips 6 thus formed are downwardly bent, either at right angles to the tray, as shown in Figure 6, or at an angle 70 rearwardly or forwardly, as shown in Figures 7 and 8. These lips rest upon the riffle 3 and are passed tightly thereon so that no liquid can pass under the same.

The rows of holes 5 are placed in staggered relation to each other so that there is no free continuous passage from one end to the other under the tray 4. That is, the pulp, in passing through the sluice box must impinge upon the depending lips 6. The 80 action of the riffle is such that as the pulp flows through the box, first downwardly through the openings 5, and then around the fingers or lips 6, eddies are formed which tend to throw the metal held in suspension in the pulp, downwardly so that it will be caught in the vertical riffle 3. The tray 4 may be formed of metal or any other material which is found desirable.

Having described my invention, I claim: 90

1. In a sluice box, a vertical riffle in said box, a plate spaced above said riffle, said plate having rows of openings therein, said rows being in staggered relation each to the other, and depending lips extending from 95 the plate and resting on said riffle.

2. In a sluice box, a vertical riffle in said box, a plate spaced above said riffle, said plate having rows of openings therein, said rows being in staggered relation each to the 100 other, and depending lips extending from the plate and resting on said riffle, said lips being formed by the sections cut out to form the openings in the plate.

3. In a sluice box, a riffle in the bottom of 105 said sluice box, said riffle being formed with transversely extending grooves therein, a plate spaced above said riffle, said plate having openings cut therein, and lips bent downwardly from the plate and resting on the 110 riffle.

4. In a sluice box, a riffle in the bottom

of said sluice box, said riffle being formed with transversely extending grooves therein, 10
with transversely extending grooves therein, said riffle being removable from the sluice
a plate spaced above said riffle, said plate
having openings cut therein, and lips bent
downwardly from the plate and resting on
the riffle, said lips being set in rows and
adjacent rows being in staggered relation.
5. In a sluice box, a riffle in the bottom
of said sluice box, said riffle being formed
with transversely extending grooves therein,
said riffle being removable from the sluice
box and separate from the bottom thereof, a
plate spaced above said riffle, said plate hav-
ing openings cut therein, and lips down-
wardly bent from the plate and resting on 15
the riffle.

In testimony whereof, I affix my signature.

RICHARD REA.
